UNITED STATES PATENT OFFICE.

JOHN SPRINGER, OF CLINTON, WISCONSIN.

FURNACE.

SPECIFICATION forming part of Letters Patent No. 363,261, dated May 17, 1887.

Application filed May 27, 1886. Serial No. 203,443. (No model.)

To all whom it may concern:

Be it known that I, JOHN SPRINGER, of Clinton, in the county of Rock and State of Wisconsin, have invented new and useful Improvements in Heating-Furnaces; and I do hereby declare that the following is a full, clear, and exact description thereof, reference being had to the accompanying drawings, which form a part of this specification.

10 This invention relates to certain new and useful improvements in the construction of heating-furnaces.

15 The object of the invention is to provide novel means for regulating the draft, taking the air for the same from the floor, or the lower stratum of air in the furnace-room, and feeding the same to the fire either below the grate and up through the same or above the fire near the top of the combustion-chamber when it is 20 desired to check the fire. As this stratum of air is generally foul, this exposure to the fire generally destroys the noxious features of the same.

25 Another object is to draw the lower stratum of air from the room above and feed it also to the combustion-chamber, whence it passes off through the exit-flue from such combustion-chamber.

30 Another object is that as the fouler stratum of air is thus drawn into the combustion-chamber of the furnace a circulation of the remaining air is obtained by providing means for admitting it into the air-chamber of the furnace, whence it is discharged in a heated condition, 35 thus adapting the furnace for use in upper rooms as well as in the cellar and basement, and avoiding the necessity of a connection with the air outside to feed the air-chamber of the furnace, the invention being designed especially as an improvement on the furnace described and shown in Patent No. 336,765, issued to me on the 23d day of February, 1886.

40 The invention consists in the peculiar construction of the various parts of the furnace and their combination, as more fully hereinafter described and claimed.

45 Figure 1 is an elevation of my improved furnace. Fig. 2 is a rear plan of the door. Fig. 3 is a vertical cross-section of the door. Fig. 50 4 is a view of the L-shaped damper-slide, which operates within the door. Figs. 5 and 6 are

vertical central cross-sections at right angles to each other.

5 In the accompanying drawings, A represents the shell of a heating-furnace, having a combustion-chamber, B, and a grate, C.

D is a hollow base, having a series of holes, a, in its walls, through which air is admitted to the air-chambers, which are located on each side of the combustion-chamber. These openings are provided with a slide damper or dampers, b, (shown in dotted lines,) and operated in 6c the usual way by a handle protruding through the slot c.

H is the outer drum, J the smoke-flue, and 65 K the spiral flange, the same as shown in my patent above referred to.

E is a chamber or open-top box secured to the front of the base, but having no communication with its interior. In the front wall of 70 this box are a series of apertures, g, having a sliding damper to uncloze or close them at will, and operated by the handle h, which protrudes through a slot in such front wall.

F is a hollow door, closed on all sides except 75 the bottom, and when the door is shut it forms a prolongation of the open-top box beneath it. There are apertures i cut in the inner wall of the door, which lead into the ash-pit or under the grate C. Just above these openings there 80 is a diaphragm, k, which would cut off any communication with the space above were not such diaphragm provided with perforations n. An L-shaped sliding damper, m, operated by means of a handle, o, protrudes through a slot, 85 r, in the front wall or plate of the door F, the whole so arranged as to uncloze the openings i and close the apertures n in the diaphragm, or the opposite, as desired.

Near the top of the door, and in the inner 90 wall thereof, there is a series of apertures, s, through which the air escapes into the combustion-chamber above the fire when the apertures i are closed and those in the diaphragm are open.

G is a pipe by means of which air is taken from the floor of a room above and carried into the open-top box E, whence it is admitted to the interior of the furnace, as described, and through the hollow door.

95 What I claim as my invention is—

1. The combination, with a furnace and the

combustion-chamber thereof, of a hollow door perforated on the inside and open at the bottom, the remainder of its sides being imperforate, an open-top box, E, provided with apertures g, and the damper-controlling aperture g below the bottom of said door, substantially as and for the purpose specified.

2. The combination, with a furnace and the combustion-chamber thereof, of a hollow door, 10 constructed as described, having its inner wall perforated near its top and bottom, a perforated diaphragm between the perforations at the top and those at the bottom, through which, when the perforations in the diaphragm are 15 open, air will be admitted through the upper perforations in the door to the said combustion-chamber, and a damper controlling the perforations in the diaphragm, substantially as described.

20 3. In combination with a furnace, a hollow open-bottomed door perforated near the top and bottom, as described, a perforated diaphragm therein, and an L-shaped sliding

damper by means of which the lower series of perforations in the rear wall of the door and 25 the perforations in the diaphragm are closed or unclosed, substantially as set forth.

4. In combination with a furnace having a hollow door with perforate inner wall and open at the bottom, as described, an open-top box 30 attached to the base of the furnace and having dampered apertures, such box forming a lower continuation of the chamber in the door when the latter is shut, as and for the purpose described.

5. In combination with a furnace having a hollow door with a perforate inner wall and open at the bottom, and open-top box, as described, a pipe communicating with such box at one end and with the room above that in 40 which the furnace is situated, as and for the purpose specified.

JOHN SPRINGER.
